UNITED STATES PATENT OFFICE.

CHARLES H. PORTER, OF ROCKFORD, ILLINOIS.

DESIGN FOR A FRAME FOR FIRE-GRATES.

SPECIFICATION forming part of Design No. 24,478, dated July 16, 1895.

Application filed May 31, 1895. Serial No. 551,328. Term of patent 7 years.

To all whom it may concern:

Be it known that I, CHARLES H. PORTER, a citizen of the United States, residing at Rockford, in the county of Winnebago and State of Illinois, have invented and produced a new and original Design for Frames for Fire-Grates, of which the following is a specification.

In the accompanying drawing is shown a perspective view of a frame embodying my design.

One of the leading features of my design consists in the fluted column forming the vertical sides of the frame.

Another leading feature consists in the capitals at the upper ends of the columns.

Another leading feature is the frieze, suitably ornamented, having its center portion depressed, and another leading feature is the cornice, suitably ornamented, having its center portion depressed.

The frame is intended for use in connection with a mantel and is composed of vertical sides and a top portion connecting the sides,

a more minute description of which will now 25 be given. The sides are made up of a base 1 and a column 2, having its face provided with lengthwise flutes 3 and its inner edge having a beaded molding 4. At the upper end of each column is located a capital 5, extending 30 some distance beyond the face of the column. A frieze, composed of the end sections 6 and center portion 7, connects the columns and is suitably ornamented. The center portion is depressed, leaving the end sections 35 standing out. The lower edge of the center portion has a beaded molding 8. A cornice is located above the frieze, having the end sections 10 extending beyond the center section 11 and suitably ornamented. 40

I claim as my invention—

The design for a frame for fire grates substantially as herein shown and described.

CHARLES H. PORTER.
